[57] CLAIM

The ornamental design for a luggage handle, as shown and described.

DESCRIPTION

FIG. 1 is a top plan view of a luggage handle showing my new design;

FIG. 2 is a front elevational view;

FIG. 3 is a cross-sectional view taken along line 3—3 of FIG. 2;

FIG. 4 is an enlarged scale fragmentary cross-sectional view taken along line 4—4 of FIG. 2;

FIG. 5 is an enlarged scale fragmentary rear elevational view taken in the direction of line 5—5 of FIG. 3;

FIG. 6 is an enlarged scale cross-sectional view taken along line 6—6 of FIG. 2;

FIG. 7 is an enlarged scale fragmentary cross-sectional view of one of the conical protuberances shown in FIG. 5; and

FIG. 8 is a rear elevational view.

FIG. 13 4FIG. 4FIG. 5FIG. 6FIG. 7

FIG-8
